UNITED STATES PATENT OFFICE.

CHARLES H. ADAMS, OF FREELAND, MICHIGAN.

SEAL-LOCK.

SPECIFICATION forming part of Letters Patent No. 393,876, dated December 4, 1888.

Application filed September 10, 1888. Serial No. 285,046. (No model.)

To all whom it may concern:

Be it known that I, CHARLES H. ADAMS, a citizen of the United States, residing at Freeland, in the county of Saginaw and State of Michigan, have invented certain new and useful Improvements in Seal-Locks for Freight-Car Doors, of which the following is a specification, reference being had therein to the accompanying drawings.

10 This invention relates to new and useful improvements in seal-locks for freight-car doors; and the invention consists in the peculiar construction and arrangement of the parts, all as more fully hereinafter described.

15 In the drawings which accompany this specification, Figure 1 is an elevation of a freight-car door, showing my improved seal-lock applied thereto. Fig. 2 is an enlarged elevation of my seal-lock. Fig. 3 is a detached perspective view of the same. Fig. 4 is a vertical central section thereof. Fig. 5 is a perspective view of the seal, and Fig. 6 is a cross-section on line *x x* in Fig. 2.

25 A is a bed-plate by means of which the device is attached to the rear end of the car-door, suitable screw-holes, *a*, being provided for therein.

30 B is a spring-latch secured near the upper end of the bed-plate and terminating in a handle, C.

D is a strap which confines the spring-latch.

35 E is a locking-tongue secured to the spring-latch and adapted to project through the slot F in the bed-plate and a corresponding slot in the door sufficiently to prevent the opening of the door by projecting over the jamb of the door when the spring-latch is depressed.

40 G is a locking-key adapted to hold the locking-latch down upon the bed-plate when inserted transversely through the key-seat *b*, formed in the confining-strap D. This key is preferably carried by means of the chain H alongside the device.

45 I is a lead seal provided with the shank *d*.

J and J' are corresponding apertures in the bed-plate and in the locking-latch to receive the shank of the seal. The aperture J is preferably provided with the conical nipple K, which projects from the face of the bed-plate, and the corresponding recess, J', is adapted

to receive it on the under side of the spring-latch.

M is a riveting-head secured at the bottom of the aperture J some distance back of it, to form the recess N to permit rivet-heading the shank of the seal, a suitable bridge, O, leading the seat to the bed-plate, as will be understood from reference to Fig. 6.

V is a sealing-tool provided with the driving-head T and the seal-head R, which carries an appropriate mark, letter, or numeral, and an abutment, P, is formed on the upper end of the tool to engage with the strap D, as shown in Fig. 4.

55 In practice, the parts being constructed and arranged as described, they are intended to operate as follows: The normal tension of the spring-latch B withdraws the tongue E sufficiently to permit of freely opening or closing the door; but if the spring-latch is depressed the tongue E impinges against the jamb of the door, and thereby prevents the opening of the same. To seal the car, the seal is inserted 60 with its shank into the aperture J' of the locking-latch. Then the sealing-tool is inserted, 65 as shown in Fig. 4, and by grasping the handle C and the handle of the sealing-tool the locking-latch will be depressed and the stud of the seal entered into the aperture J of the bed-plate. By exerting sufficient pressure the 70 riveting-head M will then upset or rivet-head the shank of the seal and impart the mark of the sealing-head on the seal. By inserting the key into the keyways of the confining-strap 75 any accidental displacement of the locking-latch is prevented. Any tampering with the car is prevented without detection, as the opening of the door cannot be effected without breaking the seal, the replacement of 80 which without the sealing-tool and its distinguishing mark cannot be effected without being plainly noticeable. To adapt the device 85 for use with the ordinary car-seals, which are secured to wires or tins, I provide the end of the key with the slots *c*, suitable to receive 90 such wires or tins.

95 The object of providing the apertures J with the nipple and forming the corresponding recess around the aperture J' to receive the shank is to prevent the spreading of the shank 100

the shank of the seal in any other way but the one provided by the rivet-head, as such nipple entirely 15 confines the shank except a small portion of its end, which projects beyond to form the rivet-head.

What I claim as my invention is—
1. In a seal-lock, the combination of the bed-plate secured to the door, the spring-latch secured thereto and carrying a locking-tongue 10 working through a slot in the bed-plate and door, the confining-strap over the latch provided with the transverse keyway, the key 15 adapted to engage therein, the apertures in the bed-plate and latch to receive the shank 20 of the seal, and the riveting-head secured behind the bed-plate, the parts being arranged to operate in connection with the lead seal 25 and the shank, substantially as and for the purpose described.

2. In a seal-lock, the combination of the bed-plate secured to the door, the spring-latch secured thereto and carrying the locking- 30 tongue working through a slot in the bed-plate and door, the strap over the spring-latch

provided with the transverse keyway, a key 25 adapted to engage therein and having the slots to receive the ordinary car-seals, and of the sealing device consisting of the apertures J and J', and the riveting-head M, and the sealing-tool, substantially as described.

3. In a seal-lock, the combination of the bed-plate A, the spring-latch B, secured thereto and carrying the tongue E, the confining-strap D, having transverse keyway, the locking-key G, adapted to engage therein and provided with the apertures c, the apertures J and J', the nipple K, the riveting-head M, and the sealing-tool V, having the driving-head T, the sealing-head R, and the abutment P, the parts being arranged to operate substantially as and for the purpose described.

In testimony whereof I affix my signature, in presence of two witnesses, this 22d day of August, 1888.

CHARLES H. ADAMS.

Witnesses: E. F. GOULD, CHAS. DIETIKER.
